UNITED STATES PATENT OFFICE.

LOUIS A. GABLE, OF LANCASTER, PENNSYLVANIA.

DESIGN FOR A COMBINATION TOOTH-CLEANER AND SUPPORT.

58,669.

Specification for Design.

Patented Aug. 9, 1921.

Application filed December 27, 1920. Serial No. 433,495. Term of patent 14 years.

To all whom it may concern:

Be it known that I, LOUIS A. GABLE, a citizen of the United States, residing at Lancaster, in the county of Lancaster and State of Pennsylvania, have invented a new, original, and ornamental Design for a Combination Tooth-Cleaner and Support, of which the following is a specification, reference be-

ing had to the accompanying drawing, forming part thereof.

The figure is a perspective view of a tooth cleaner and support showing my new design.

I claim:

The ornamental design for a combination tooth cleaner and support, as shown.

LOUIS A. GABLE.
